UNITED STATES PATENT OFFICE.

F. WALTER GUIBERT, OF DETROIT, MICHIGAN.

PROCESS OF FORMING METALLIC ARTICLES.

1,259,224.

Specification of Letters Patent. Patented Mar. 12, 1918.

Application filed January 11, 1917. Serial No. 141,835.

To all whom it may concern:

Be it known that I, F WALTER GUIBERT, a citizen of the United States of America, residing at Detroit, in the county of Wayne 5 and State of Michigan, have invented certain new and useful Improvements in Processes of Forming Metallic Articles, of which the following is a specification, reference being had therein to the accompanying drawings.

The invention relates to the art of forming articles by die-casting, and it is the object of the invention to secure in addition to the advantages incident to the ordinary die-casting process the further advantage of greater strength and resistance in the finished product. To this end the invention consists in the novel process, and further in the product as hereinafter set forth.

20 In the drawings:

Figure 1 is an elevation of a hexagonal nut formed by my process;

Fig. 2 is a bottom plan view thereof;

Fig. 3 is a cross-section through the die, 25 showing the reinforcement therein prior to the casting process;

Fig. 4 is a section through the cast, reinforced nut as removed from the die;

Fig. 5 is a similar view after the threading operation.

While my process is applicable to various manufactured devices, I have confined

the description to the specific process of forming die-cast nuts.

A is a metallic washer of steel or other 35 material, possessing the requisite strength for the threads of the nut. This washer is non-circular in contour, being preferably of polygonal form corresponding to the shape of the nut. In forming my nut a 40 washer A is placed within the die in engagement with a suitable mandrel B, and the sections C and C' of the die are then closed around the same. This will center the washer within the mold cavity, so that when 45 the molten metal is filled therein the washer will be embedded, as illustrated in Fig. 4. The threading of the nut is then accomplished by any suitable apparatus, resulting 50 in the structure shown in Fig. 5.

What I claim as my invention is:

1. The process of forming nuts, comprising the die-casting of a hollow soft metal cap upon a hard metal washer and then the threading of the inner wall of said 55 washer.

2. The process of forming nuts, consisting in die-casting a hollow soft metal covering about a hard metal washer, the inner faces of the covering and washer being in alignment, and in threading both inner faces.

In testimony whereof I affix my signature.

F. WALTER GUIBERT.
